UNITED STATES PATENT OFFICE.

FRANK P. MILLS, OF BERKELEY, CALIFORNIA.

ADJUSTMENT ATTACHMENT FOR HYDRAULIC TESTING APPARATUS.

Application filed January 24, 1921. Serial No. 439,638.

To all whom it may concern:

Be it known that I, FRANK P. MILLS, a citizen of the United States, residing at Berkeley, in the county of Alameda and State of California, have invented certain new and useful Improvements in Adjustment Attachments for Hydraulic Testing Apparatus, of which the following is a specification.

10 My invention is an adjustment attachment for hydraulic testing apparatus, for adjusting the position of the pressure cylinder and piston with relation to the work table.

Referring to the annexed drawing in 15 which my invention is illustrated and which forms a part of this specification:

Figure 1 is a vertical longitudinal section of a hydraulic testing apparatus and my adjustment attachment attached thereto.

20 Figure 2 is a horizontal section of the testing apparatus taken on line 2-2 of Figure 1.

A hydraulic testing apparatus to which my invention is attached will first be described. Through a horizontal work table 1 at the corners thereof extend vertical rods 2, on the lower end of which rods screw nuts 3 and 4 respectively against the lower and upper side of the work table. A cylinder 30 head 5 is provided with apertures 6 at its corners through which apertures extend the rods 2. Said head is secured to the upper end of a cylinder 7 by means of bolts 8 which extend through an external flange 9 on the upper end of the cylinder into the head. Nuts 10 screw on the rods 2 which are threaded, upon which nuts rest the cylinder head 5 whereby the cylinder 7 may be supported at different elevations. Wing nuts 40 11 screw on the rods 2 against the upper side of the cylinder head 5 for holding the head firmly on the nuts 10. A piston 12 reciprocates in the cylinder 7, to which piston is connected a rod 13 which extends 45 through a stuffing box 14 in the lower head of the cylinder. A press head 15 is mounted on the lower end of the piston rod 13, said head being made in two sections 16 and 17 secured together by bolts 18, the upper section being provided with a central aperture 19 through which the rod 13 extends, and with a recess 20 in its under side below said aperture in which fits a head 21 on the lower end of the piston rod. A pipe 22 extends 55 below the working table and upwardly through the center thereof, said pipe being

controlled by a valve 23. A port 24 extends through one side of the lower head section 16 and through the center of the under side thereof, the end of said port at 60 the side of the section being connected to a pipe 25 controlled by a valve 26. A pipe 27 controlled by a valve 28 extends into the cylinder 7 through the upper head 5. A pipe 29 controlled by a valve 30 extends into 65 the cylinder 7 through the lower head thereof.

My adjustment attachment includes a plate 40 mounted on the upper end of rods 2, a cylinder 41 mounted on said plate, a 70 piston 42 mounted to reciprocate in said cylinder, and a piston rod 43 connected at its lower end to the cylinder head 5. The cylinder 41 has a stuffing box 44 at its lower end which extends through an opening 45 in the plate 40, the lower head of the cylinder resting on said plate. The plate 40 has apertures 46 through which extend the upper end of the rods 2. Nuts 47 screw on the upper end of rods 2 on which nuts rest the 80 plate 40. Nuts 48 screw on the upper end of the rods 2 against the top of the plate 40, locking the plate on the rods 2 against the nuts 47.

A valve 49 controls the air in the cylinder 41. The valve 49 includes a piston 50 which is controlled by a rod 51, said rod passing through a gland 52 in the end of the valve 50. An air line 53 enters at the lower end of the valve 49, and a branch 54 enters the 90 top of said valve. An intake 55 enters the bottom of the cylinder 41, the mouth of which is directly opposite the line 53. A cylinder exhaust 56 is positioned slightly above the bottom of the cylinder 41, and 95 enters the side of the valve 49 above the pipe 55. A valve exhaust pipe 57 is adapted to lead the air from the valve 49 when the annular groove 58 in the piston 50 registers with the pipes 56 and 57. During this 100 period the lower end of the piston 50 rests over the line 53 and pipe 55 to prevent any intake of air.

The pipe sections, joints, couplings, and so forth, indicated 59, 60 and 61 which are 105 to be tested are placed one upon another with gaskets 62 therebetween, upon the work table 1 over the upper end of the tube 22 and under the inner end of the port 24. Water under pressure is introduced through 110 pipe 27 into the top of the cylinder 7 which forces the piston 12 downwardly and the

pressure head 15 tightly into engagement with the upper end of the part 61. Water under great pressure is introduced through pipe 22, parts 59, 60 and 61, port 24 and pipe 25 to test said parts. When the parts have been tested, water under pressure is introduced through pipe 29 into the cylinder 7, raising the piston 12 and the pressure head 15, the water in the top of the cylinder being forced out through the pipe 27. The pipe parts 59, 60 and 61 are then removed. If the cylinder 7 is too low for the length of pipe to be tested, the nuts 11 are turned until they are raised a suitable height; compressed air is then introduced through pipe 55 into the cylinder 41 raising the piston 42 and the head 5, cylinder 7 and head 15; the nuts 10 are then screwed up to the head 5; the nuts 11 are then screwed down to the head, and the compressed air is then allowed to pass out of the cylinder 41 through pipe 56. To lower the cylinder 7 and head 15, compressed air is introduced into the cylinder 41 to hold up the piston 42, cylinder 7 and pressure head 15; the nuts 10 are screwed down to the desired level; the air is let out of the cylinder 41 through pipe 56 until the head rests on nuts 10 and the nuts 11 are then screwed down on the head.

Having described my invention, I claim:

1. In combination with a hydraulic testing apparatus, including a pressure cylinder and a press head, a piston in said cylinder, a rod secured to said piston and said press head, and means to exert pressure on

either side of said piston, means for raising and lowering the pressure cylinder and press head of said apparatus, and means for securing said cylinder at different elevations whereby said cylinder and press head may be adjusted to accommodate various sizes of work. 40

2. In combination with a hydraulic testing apparatus, including a pressure cylinder and a press head, a piston in said cylinder, a rod secured to said piston and said press head, and means to exert pressure on either side of said piston, and adjustment means for raising and lowering the pressure cylinder of said apparatus, said adjustment means including a compressed air cylinder, piston, and a piston rod, the piston rod being connected to the pressure cylinder, whereby said cylinder and press head may be adjusted 50 to accommodate various sizes of work. 55

3. In combination with a hydraulic testing apparatus, including a pressure cylinder and a press head, a piston in said cylinder, a rod secured to said piston and said press head, and means to exert pressure on either side of said piston, vertical rods on which the pressure cylinder is adjustably mounted, a plate mounted on said rods above said cylinder, a compressed air cylinder, piston 65 and piston rod mounted on said plate, the piston rod being connected to the head of said pressure cylinder, whereby said cylinder and press head may be adjusted to accommodate various sizes of work. 70

In testimony whereof I affix my signature.
FRANK P. MILLS.
